(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a front perspective thereof, in which a wristband in dot-dot-dash broken lines is provided to depict an example environment.

The dashed broken lines in the figures depict portions of the electronic device that form no part of the claimed design. The dot-dot-dash broken lines in FIG. 9 showing the wristband depict environmental structure and form no part of the claimed design.
